UNITED STATES PATENT OFFICE

THEODORE W. SMITH, OF INDIANAPOLIS, INDIANA, ASSIGNOR TO PETER C. REILLY, OF INDIANAPOLIS, INDIANA

PROCESS OF IMPREGNATING TIMBERS

Application filed July 27, 1928. Serial No. 295,798.

This invention pertains to an improved method of impregnating timbers.

Timbers taken from the same tree, as well as timbers taken from different trees, vary in physical characteristics and hence vary as to the amount of liquid which they will absorb or which may be forced into the same under the like or similar conditions.

Thus, for instance, in the treatment of railroad ties a hard, solid or close grained tie will resist penetration of the impregnating liquid whereas a soft or spongy tie, and which is mechanically short lived, will not only readily receive the liquid but in some cases as where the tie is thoroughly dry and warm will have a tendency to absorb the liquid and this without the application of pressure upon the liquid. From this it will be seen that mechanically good and solid ties will not in the ordinary course of treatment take up the requisite amount of impregnating liquid whereas the physically poorer tie will take up more than is requisite for adequate protection.

Under the usual specifications as to the preservation of ties or timbers a given amount of preservative liquid, per cubic foot of wood, is required; it will therefore be seen that where a number of ties are impregnated at one and the same time—or where the ties are individually treated and subject to the same treatment uniformity of impregnation does not obtain due to the physical differences of timber above mentioned. It is, of course, a waste of material to over impregnate a mechanically weak tie and it is likewise detrimental to the longevity of a structurally perfect tie not to sufficiently impregnate the same.

Under the method herein set forth all timbers—say ties—may be given the desired degree or amount of impregnation with the assurance that each and every tie will have an equal amount of liquid forced into the same.

Stated in general terms, my method may be

45 said to comprise the following steps:

Placing a tie within a cylinder, then passing an amount of liquid equal to the volume of the empty cylinder into the cylinder in which the tie is placed, allowing the excess of liquid 50 to flow outwardly therefrom, segregating a

portion of the outflowing liquid, which portion shall be equal to the amount which it is desired shall be injected or forced into the tie to secure the necessary or specified impregnation, and finally forcing such amount into the tie.

Stated in another way, the method may be said to comprise measuring the cubical content of the tie by flowing a quantity of liquid equal to the cubical capacity of a container in which the tie is placed into said container, allowing the excess liquid to overflow from the container, segregating a portion of the outflowing liquid, said portion bearing a fixed ratio to the cubical content of the timber, and thereafter forcing such segregated portion into the timber.

Various forms of apparatus may be employed to carry out the method hereinafter more specifically set forth but in order that the invention may be more readily understood and a practical form thereof set forth reference is had to the annexed drawings wherein:

Figure 1 is a perspective view of a treating cylinder and so much of the appurtenant apparatus parts as is necessary to carry out the method,

Figure 2 a perspective view of a weir with the cover thereof removed which is employed for segregating a portion of the liquid 70 passing into the cylinder when the tie is in place therein,

Figure 3 a top plan view of the weir,

Figure 4 a vertical sectional view of the weir, and

Figure 5 a top plan view of the weir with the cover removed showing the relationship of the various parts.

It is to be understood, of course, that the apparatus hereinafter described is to be taken as merely indicative of one means whereby the method may be practiced.

In another application a more detailed showing of an apparatus, which is automatic in its action, is set forth and claimed, hence 95 no claim is made herein broadly to any such mechanism.

In the drawings, 1 denotes a cylinder having removable heads or ends 2 and 3 which may be of any approved form. A single head 100

may be employed if desired although where the apparatus is employed with tie presenting and removing mechanism the presence of the two heads is found advantageous.

5 Opening into the cylinder is a valved liquid supply pipe 4 in which is mounted a metering device 5 designed to show the attendant when an amount of impregnating liquid equal to the known cubical content of the cylinder has 10 passed through the pipe 4. The cylinder is also provided with a valved outlet, designated by 6, which opens through a port 7, Figures 4 and 5, into a weir denoted generally by 8.

15 The weir, as will be seen, comprises a cylindrical body, the lower end of which is closed except for the ports which enter the same. Extending upwardly from the bottom 9 of the weir is a vertically disposed partition 10 and extending outwardly to the opposite 20 sides of the inner wall of the cylindrical body 8 are two other partitions 11 and 12. Partition 10 extends to the full height of the body 8 whereas the partitions 11 and 12 are lower. These three partitions form three chambers 25 within the weir, to wit: an inlet chamber into which the port 7 opens and two measuring and discharge chambers into which the discharge ports 13 and 14 open.

30 Mounted within the inlet chamber of the weir is a blade or plate 15, the innermost edge whereof is rounded and fits into a rounded recess 15^a formed in the vertical inner edge of the partition 10. This rounded portion of the blade extends upwardly as at 16 through 35 the cover 17 of the weir and has attached to its upper end a laterally extending finger 18, the outermost end whereof is bent downwardly and carries a locking screw 19. The face of the cover below the indicator arm 18 is 40 graduated so as to show the position of the blade or vane 15 with reference to the inlet chamber and consequently to indicate the proportionate flow of the liquid from the inlet chamber to the outlet chambers from which 45 the ports 13 and 14 discharge.

Extending inwardly from the walls 11 and 12 below the blade or vane 15 is a baffle or partition 20 which acts to prevent upward surge of the liquid as it is flowing into the weir.

50 Vent pipes 21 and 21^a are mounted in the cover to prevent the weir from becoming trapped or air bound.

The port 14 is connected with a pipe 22 which leads to the storage tank (not shown) 55 from which the supply of impregnating material is drawn and pumped back as occasion requires through the intake pipe 4 and through the metering device 5.

Port 13 is interconnected with a pipe 23, 60 which latter extends to a cylinder 24. The line 23, contains a check valve 25 opening toward the cylinder 24. A branch line 26 is interconnected with the pipe 23 intermediate the cylinder 24 and the check valve 25, said 65 line 26 being connected to the cylinder 1. A

check valve 27 is interposed in the line 26, said valve opening in the direction of the cylinder 1, or opposite to that of the check valve 25.

An air line 28 connected to any suitable source of air under pressure and provided with a control valve 29 opens into the cylinder 24.

A vent cock 30 is also in communication with the cylinder 24 in order that the air may be allowed to escape therefrom when the impregnating liquor which is to be forced into the tie or timber under treatment flows from the weir into the cylinder 24.

The air entering the pipe 28 may act directly upon the upper face of the liquid contained in the cylinder 24 to force the same outwardly when desired, or it may act upon the upper face of a piston 31 mounted therein and provided with a piston rod 32, which tends to guide and properly position the piston.

A draw-off or drain cock 33 is provided for the cylinder or tank 1 and such draw-off may, of course, lead to the reservoir where the supply of impregnating liquid is maintained. It is thought that the operation of the apparatus will be fully understood but it may be briefly stated as follows:

A tie being placed within the cylinder 1, the heads 2 and 3 thereof will be closed. Thereupon liquid to the amount of the cubical content of the cylinder will be allowed to flow through the intake pipe 4, the amount being readily ascertainable through the meter 5. An amount of the liquid equal to the cubical content of the tie will, of course, pass through the valved outlet 6 and through the weir. The wing or blade 15 of the weir will have been adjusted to such a position that the desired amount or proportion of the overflow from the tank 1 will pass from the opening 13 into the line 23 and hence into the cylinder 24. The remaining portion will pass through the line 22 to the storage tank.

Before starting the operation it is necessary to adjust the vane of the weir so that the requisite amount of oil to be injected into the tie or timber will be diverted through the pipeline 23 into cylinder 24 from which the oil can be forced through pipeline 26 into cylinder 1.

As will readily be appreciated, by swinging the vane 15 to one or the other side with reference to the opening 7 the amount of liquid which will pass over the walls 11 and 12 may be determined.

By swinging the arm 18 to the right, Figures 3 and 5, the flow over the wall 12 into the outlet 13 will be decreased whereas the flow over the wall 11 and into the discharge opening 14 will be increased.

When the requisite amount of liquid has been metered into the cylinder 1 the valve in the pipe 4 is cut off as is also the valved outlet 6. The operator will then open the air valve in the line 28, the vent valve 30 being

meanwhile closed, and air under pressure will displace the liquid from the cylinder 24 and force it through the pipe 26 and past the check valve 27 into the cylinder 1 and the pressure is maintained until the rod 32 is moved inwardly to such an extent as to indicate that the amount of liquid contained within the cylinder 24 has been forced into the cylinder 1 and consequently into the timber placed therein.

From this it will be seen that irrespective of the physical nature of the timbers or ties each piece will have forced into the same, under the above operation, an equal quantity of liquid. Thus a good tie will obtain its full amount as will a poor tie, considered from its physical structure, and the latter will not be impregnated with surplus liquid, which may be looked upon as wastage when it is so applied.

It is to be understood that the apparatus herein illustrated is to be considered more or less as a diagrammatic showing and in actual practice the opening and closing of the heads 2 and 3 for the introduction and removal of the tie or timber and the manipulation of the valves controlling the introduction and withdrawal of the liquid and the pressure which is applied to the liquid to produce impregnation are automatically controlled and work in timed relation.

No claim is made herein to the apparatus shown and described as the same forms the subject matter of my copending application filed September 3rd, 1929, Serial Number 390,142.

What is claimed is:

1. That method of effecting uniform impregnation of timbers irrespective of their physical characteristics which consists in individually determining the cubical content of each timber as it is treated by placing the same in a container of known cubical capacity; thereafter passing liquid into said container in a quantity equal to the cubical content of the container and allowing the excess liquid to flow out of the container; segregating a portion of the outflowing liquid, said portion being in a fixed ratio to the cubical content of the timber; and finally forcing said segregated portion back into the container whereby liquid in a quantity equal to such segregated portion will be forced into the timber.

2. That method of effecting uniform impregnation of timbers possessing different physical characteristics affecting their capacity to receive or absorb an impregnating liquid which consists in individually determining the cubical content of each timber as it is treated by placing the same in a container of known cubical capacity; thereafter passing liquid into said container in a quantity equal to the cubical content of the container and allowing the liquid in an amount

equal to the cubical content of the timber to flow out of the container; segregating a proportionate amount of said outflowing liquid and finally forcing said segregated portion back into the container whereby liquid in a quantity equal to such segregated portion will be forced into the timber.

3. That method of effecting impregnation of timbers with a predetermined amount of preservative liquid irrespective of the physical characteristics of said timbers which consists in placing the timbers one by one in a container; passing a quantity of liquid into the container in amount equal at least to the cubical content of the container and allowing the excess liquid displaced by the timber to flow from the container; and thereafter forcing a predetermined portion of the excess liquid back into the container.

4. That method of uniformly impregnating pieces of timber having varying physical characteristics in a container of known cubical capacity which consists in determining the cubical volume of each piece of timber by the immersion thereof in a body of liquid equal to the cubical capacity of the container; and thereafter forcing into each piece of timber an amount of liquid equal to a determinate proportion of the liquid initially displaced from the container by the timber when determining its cubical volume.

In testimony whereof I have signed my name to this specification.

THEODORE W. SMITH.
